DESIGN FOR A BOTTLE

Jerome W. Marrow, Chicago, Ill., assignor to J. W. Marrow Manufacturing Company, Chicago, Ill., a corporation of Illinois

Application October 21, 1936, Serial No. 65,398

Term of patent 7 years

To all whom it may concern:

Be it known that I, Jerome W. Marrow, a citizen of the United States, residing at Chicago, in the county of Cook and State of Illinois, have invented a new, original, and ornamental Design for a Bottle, of which the following is a specification, reference being had to the accompanying drawing, forming a part thereof.

In the drawing:

Fig. 1 is a side elevational view of a bottle showing my new design.

Fig. 2 is a top plan view thereof.

I claim:

The ornamental design for a bottle substantially as shown.

JEROME W. MARROW.
